SETH D. PAUL, OF WOONSOCKET, RHODE ISLAND.

Letters Patent No. 99,342, dated February 1, 1870.

IMPROVEMENT IN SELF-ACTING MULE FOR SPINNING.

The Schedule referred to in these Letters Patent and making part of the same.

To all whom it may concern:

Be it known that I, SETH D. PAUL, of Woonsocket, in the county of Providence, and State of Rhode Island, have invented new and useful Improvements in Self-Acting Mules for Spinning Yarn; and I do hereby declare that the following is a full, clear, and exact description thereof, reference being had to the accompanying drawings, by the letters and figures marked thereon.

My improvements are principally designed for spinning woollen yarn, but the main features of the invention are also applicable to cotton-spinning.

In order that my invention may be better understood, I will first describe the successive movements required in spinning woollen yarn.

The condition of the wool when ready for spinning, is in roving or prepared sliver, wound upon spools, which are placed upon drums back of the rollers. The roving passes from the spools between the rollers, and thence to the spindles, which are in their usual position in the carriage.

When the mule is ready to start, the carriage and spindles are at the nearest point to the rolls, and when put in operation, the carriage begins to recede from the rolls, which revolve at the same time, and deliver the roving at about the same speed as the traversing of the carriage. The rolls continue delivering the roving until the carriage is about half way out, when they are stopped by what I term the roller-motion, the carriage continuing on its way out until it reaches the end of its traverse. Thus the yarn is drawn and made finer.

From the time the carriage starts out until it completes its outward traverse, the spindles run at a speed which will put the proper amount of twist in the yarn to draw the roving smoothly, and make an even and strong thread.

After the carriage is out, the spindles continue running until the yarn is sufficiently twisted. This twisting, after the carriage is out, is called "head-twist."

While the head-twist is being put in, the thread is somewhat shortened, and the carriage is made to move back sufficiently to keep the yarn at the right tension. This drawing-in motion of the carriage is effected by devices hereinafter described.

After the yarn is sufficiently twisted, the motion of the spindles is reversed, to unwind the same, so as to allow the faller-wires to come down to the proper position to guide it on the spindles when winding on. This motion of the spindles and fallers is called backing off.

After backing off, the carriage is run in to the starting-point, the spindles revolving at the proper speed for winding on the yarn.

The accompanying drawings are comprised in six sheets, designated by the letters A, B, C, D, E, and F.

In Sheet A—

Figure 1 shows a view in elevation of my mule, and Figure 2, a plan.

Sheet B shows details of shipping-mechanism—

Figure 1 showing an elevation of shipping-mechanism, and

Figure 2, a plan of same.

Figure 3 shows an end view of connecting-gears from cone-pulley to scroll-shaft, also pulley for driving cam-shaft.

Figure 4 shows a front view of forked lever for operating clutch.

Figure 5 shows a plan of cam or escape-plate, and Figure 6 shows an elevation of same.

Sheet C shows details of roller-mechanism, as follows:

Figure 1, an elevation of roller-mechanism;

Figure 2, a plan of same;

Figure 3, a front view of worm-gear and lever for operating clutch;

Figure 4, a front and side view of worm-gear, with cord and weight attached; and

Figure 5, a front and side view of lifter-stand.

Sheet D shows the twist and drawing-in mechanism, as follows:

Figure 1, an elevation of twisting and drawing-in mechanism;

Figure 2, a plan of same; and

Figure 3, a front and side view of worm-gear, with cord or chain and weight attached.

Sheet E represents the ratchet-mechanism, overhead shipping and connecting-mechanism from scroll to cam-shaft—

Figure 1 showing a plan of faller and ratchet-mechanism;

Figure 2, an elevation of ratchet-mechanism;

Figure 3, an elevation of faller-lock;

Figure 4, a front and side view of bevel finger p;

Figure 5, overhead shipping-mechanism;

Figure 6, an elevation of connecting-mechanism from scroll to cam-shaft;

Figure 7, a plan of connecting-mechanism from scroll to cam-shaft; and

Figure 8, a plan and elevation of roller in belt-guide.

Sheet F shows cone-pulley, with gear attached to hub of same for connecting with scroll-shaft—

Figure 1 being an elevation, and

Figure 2, a plan.

To produce the roller-motion, I make use of the following parts:

Clutch A, lever B, latch C, upright rod D, lifter F, worm-wheel G, pins H and I, weight J, finger K, worm L, spring 17, and stud 35.

The roller-mechanism is connected with the driving or rim-shaft 6 by the train of gears 1, 2, 3, and 4.

When the mule is ready to start, the lever B rests

upon the latch C. As the rolls revolve, the worm L moves the wheel G around until the pin H comes in contact with the latch C, and forces it from under the lever B, which is then thrown down by the spring 17, thus disconnecting the clutch A, which stops the rolls.

When the carriage returns in, the lifter F passes under the upright rod D, thereby raising the lever B and throwing in gear the clutch A. The latch C then falls back under the stud 35 by its own weight, and supports the lever B, thereby holding in the clutch A.

When the lever B drops, the worm-wheel G, which revolves on the stud 35 in said lever, is disconnected from the worm L, and turned back by the weight J, until the pin I strikes the latch C, when it rests in its first position.

Near and equidistant from the periphery of the worm-wheel G, are holes, in one of which the pin I is fixed, the others being designed to receive the pin H, which, when changed from one hole to another, operate on the latch C so as to vary the time that the rolls are in operation, and the amount of sliver delivered.

This change of time has frequently to be made, and this mode of doing it is simple and convenient, avoiding the use of change-gears.

When the rolls are run at a high rate of speed they acquire a momentum which causes them to continue their motion after the clutch A is thrown out, delivering more sliver than is desired. To obviate this, I have on that part of the clutch A, which is operated by the lever B, and slides on a key, and turns with the shaft, a bevelled surface, 15.

On the inside of the stationary cup 16, is a bevelled surface corresponding to the surface 15.

When the parts A are unclutched, the surface 15 is thrown in contact with cup 16, causing a friction and checking of the rolls.

In the twist-motion, the following parts are used:

Bevel-gear M, bevel-gear N, worm O, worm-wheel P, pin Q, pin R, finger S, cam T, finger U, lever V, cam W, (outer surface,) lever X, and weight Y.

When the mule is in, ready to start, the lever X holds the cam-shaft v in such a position that the cam W bears on the lever V, and holds the wheel P in the worm O.

When the mule starts, motion is communicated from the driving shaft 6, by gear M, gear N, and worm O, to worm-wheel P.

The carriage runs out, and, when it reaches the end of its traverse, the lever X is brought in contact with the cam T. This permits the cam-shaft v to make a quarter revolution, by means of which the carriage is stopped.

At this point the operation of putting in the head-twist begins. The wheel P continues to revolve during the putting in of the head-twist, the same as while the carriage is running out, until the pin Q comes in contact with finger S, and carries it over, so that the cam T, (which is fastened to the same shaft as finger S,) is removed from the lever X. This allows the lever X to come up, so that the cam-shaft v makes another quarter revolution, and the mule backs off.

At the same time, the cam W is brought in such a position as to admit of the disconnection of the worm-wheel P from the worm O, by dropping of its own weight, thus stopping the head-twist. Then the wheel P is turned back by the weight Y, until the pin R, striking the under side of lever V, reaches its first position.

The cam-shaft now makes still another quarter revolution, and the carriage runs in. On arriving in, the cam-shaft makes a fourth quarter revolution, and throws the worm-wheel P into the worm O, (its original position,) thus completing one round of operations.

Holes are drilled in wheel P, near its periphery.

The pin R is stationary in one of these holes, and the pin Q is changed from one hole to another, thus varying the distance from Q to R, and, consequently, varying the time required for pin Q to arrive at finger S, whereby the amount of twist put in the yarn is increased or diminished. This is a simple, convenient, and correct method of changing the twist. It is as applicable to cotton-spinning as to wool, and saves the expense of a large number of gears, and the labor of changing them.

The drawing-in motion is produced by the following parts:

Bevel-gear M, bevel Z, shell a, worm b, shaft c, cam W, collar d, worm-gear e, gear f, rack g, rod h, slide-bar i, finger l, and stand 30.

On the running out of the carriage, the stand 30, sliding under the latch m, comes in contact with the finger l, on the slide-bar i, upon which said latch is fastened, and continues to draw said bar out during the remainder of its traverse, on reaching the end of which, the cam-shaft v makes a quarter revolution, and the cam W, acting on the shaft c, throws the worm b into the gear e.

On the same stud with gear e is gear f, running in rack g.

Attached to the rack g is the rod h, connecting with the slide-bar i. The worm b, running in gear e, thereby turns gear f, which, in connection with the rack g, draws the slide-bar i.

The finger l, being in contact with the stand 30, moves the carriage back a little as the head-twist is going into the yarn.

In the operation of backing off, the mule has a tendency, from the reverse motion of the bands, to move in. To prevent this action, the stand 30 is caught by the latch m, and held by it during said operation, the slide-bar being stationary while the worm b is in gear, which is the case until after the backing off.

The advantage of attaching the latch to the slide-bar, instead of the frame, as in the usual manner, is found in the fact that it is always ready to act on stand 30, without regard to the distance the carriage is drawn in by finger l.

The operation of backing off is stopped by the dropping of that end of the lever X to which the finger 32 is attached.

The said finger now strikes the end of latch m and throws it off from stand 30, allowing the carriage to run in.

To throw the ratchet in gear after backing off, I use the following parts:

Finger n, bevel-plate o, bevel-finger p, bevel-finger q. The faller-lock 23 is connected, by the rod 24, to the finger n.

When the carriage backs off, the faller-lock drops down over the catch 25, and, at the same time, throws up the finger n, which causes the bevelled finger p to act on the bevelled surface of the plate o, forcing it toward the ratchet 21.

The bevelled finger q then acts on the ratchet 21, and presses it into the ratchet-wheel 22. The ratchet 21 remains in gear while the mule is running in after backing off.

The object of the spring r is to hold the ratchet out of gear at all times, excepting when the carriage is running in after backing off.

The cone-pulleys are attached to the main or driving and counter-shafts, and impart a gradual increase of speed to the spindles, rolls, and carriage, by raising all the working-parts of the machine, while the carriage is running out. The product of the machine is thus increased from ten to fifteen per cent. over the old method of running out at a uniform speed, or the mule may be started slower than usual, and gradually increased, so that the average speed will be the same

as by the old method, thereby requiring less labor to piece up or mend threads, while the mule is running slower at the first of the draw or stretch.

I will now proceed to describe the operation of these pulleys.

That part of the friction-clutch *t* which is operated by the forked lever *u*, slides on a key or spline, and turns with the shaft *6*, and the other part is fastened to the cone-pulley. Hence, when the parts are clutched, the shaft *6* and cone-pulley revolve together, thereby driving the mule. The said clutch is connected when the mule starts out, and remains so while it is running out, and while the head-twist is being put in.

The cam-shaft *v* then makes a quarter revolution, and the clutch *t* is disconnected by the forked lever *u*, which is operated by the cam *40*.

The pulley *s* now turns loosely on the shaft *6*, while the mule is backing off and running in.

A belt, running from counter-shaft to the pulley *W*², drives the cam-shaft, and backs off and runs in the mule.

When the mule arrives in, the parts *t* are again clutched, by the action of forked lever *u* and arm *40*.

Instead of the pulley *W*², I may use the pulley *L*² and gear *M*², for the purpose of running the cam-shaft *v*, and to back off and run in the mule, running the belt from counter-shaft to pulley *L*².

The gear *M*² connects with the gear *O*², to drive the carriage in, and also connects with and drives the cam-shaft *v*, by using the outside portion of the friction-clutch *G*² as a gear, as shown in figs. 6 and 7, Sheet E. This enables me to dispense with several gears, and also with the belt running from pulley *F*², and gives more room for other parts of the mule; or the cone-pulley *s*, extended in length to the gear *80*, can be used to run in the carriage as a second method of dispensing with the pulley *W*², the gear *80* being attached to the hub of the cone-pulley, instead of the pulley *W*², as shown in fig. 2, Sheet F.

In the shipping-motion, when the carriage is ready to start out, the belt is running from the small part of the cone-pulley *20* to the large part of the pulley *s*. As the carriage runs out, the belt is gradually guided to the other ends of the pulleys, increasing the speed as the belt is thus changed.

This shipping of the belt on the cone-pulleys is produced by the use of the following parts: shipper *7*, lever *8*, stud *9*, nut *10*, screw *11*, chain-gear *12*, chain-gear *13*, and chain *14*.

The chain *14* passes around the gears *12* and *13*, each end being attached to the carriage. As the carriage runs out, the chain is moved with it, turning the gear *12*, and communicating motion, by means of the screw *11*, nut *10*, and lever *8*, to the shipper *7*, causing it to guide the belt from one end of the pulley to the other. When the carriage returns in, the chain is carried in the opposite direction, and the belt is guided back to its first position on the pulleys.

The gear *12* is keyed to the screw-shaft *11*, and, by taking out the key, the gear turns loosely on the screw-shaft, permitting the carriage to run in and out without changing the belt on the pulleys. With this arrangement, the shipper may be set at any point on the pulleys, thus guiding the belt in one place all the time, thereby running the mule without varying the speed, if desired.

The pulley *41* runs loosely on the hub of the friction-clutch *t*.

When the mule is in, ready to start out, the belt may be set so as to be partly on this loose pulley and partly on the cone-pulley *s*. Only a part of the power of the belt would thus be applied to the cone-pulley *s* in starting the mule, thereby starting it more gently.

The screw *11* can be used either right or left hand, in the one case giving an increase, and in the other,

a decrease of speed to the mule while running out. This object can also be accomplished by arranging the chain *14* to run either over or under from the chain-gear *12*, on the screw *11*, to the carriage.

As the belt is shipped on the cone-pulleys, it inclines to the large end of the pulley *20*, rendering a guide necessary near this pulley.

For this purpose a rod, *B*², having a guide, *c*², attached, is suspended from the ceiling or floor.

This rod *B*² connects with the shipper *7*, which is extended up to meet it at *D*².

The shipper *7* moves the rod *B*² at the same time it moves the belt, thus guiding the belt on both pulleys alike.

The bolt connecting the shipper *7* and rod *B*² is moved in a slot in one or both of the ends, connected so as to allow the free movement of the shipper.

In the guide *c*² is a small pulley, *E*², for the edge of the belt to run upon, to avoid a friction of the belt on the side of the guide.

The cam-shaft *v* is driven by a belt running from pulley *F*² to the friction-clutch *G*².

This clutch is connected by the spring *t*², and disconnected by the pieces *a*² *b*² *c*² *d*² coming round and striking the bevelled surface *e*², on the escape-lever *X*.

When the escape-plate *f*² revolves, and the pieces *a*² *b*² *c*² *d*² come in contact with the bevelled surface *e*², disconnecting the friction-clutch *G*², the cam-shaft continues its motion until stopped by the action of the said pieces in striking the stop *J*². This stop *J*² and the bevelled surface *e*² are combined in one piece on the lever *X*. This is an improvement over the old method of having the bevelled surface on the four pieces *a*², *b*², *c*², and *d*².

When the cam-shaft *v* is still, something is necessary to hold some one of the pieces *a*², *b*², *c*², or *d*², in contact with the stop *J*². For this purpose I provide the spring-latch *K*².

When the cam-shaft makes a quarter revolution, and some one of the pieces *a*² *b*² *c*² *d*² strikes the stop *J*², the latch *K*² springs back of these pieces, and prevents the cam-shaft or escape-plate from turning back.

Motion is communicated to the carriage by the train of gears *1*, *2*, *3*, *6*², and *70*, connecting with clutch-gear *82*.

This clutch-gear *82* connects with the scrolls *83* and *84*, on which is a band, connecting with the carriage, by means of which the carriage is driven out.

As I use common means for running the carriage out and in, except in increasing its speed, as herein described, I have not deemed it necessary to particularly set forth these operations.

Having thus fully described my invention,

What I claim as new therein, and desire to secure by Letters Patent, is—

1. The cone-pulleys, in combination with the rolls, spindles, and carriage, by the means substantially as described, for the purpose of increasing the speed of the rolls, spindle, and carriage, while the carriage is running out.

2. The cone-pulleys, combined with the carriage, substantially as described, for the purpose of increasing the speed of the carriage while running out.

3. The clutch *A*, lever *B*, latch *C*, and worm-wheel *G*, arranged and operating substantially as described.

4. The clutch *A*, lever *B*, latch *C*, pulley *s*, pulley *20*, intermediate gears *2*, *3*, *4*, or their equivalents, in combination, for the purpose of increasing the speed of the rolls.

5. The friction-cup *16*, in combination with the bevelled portion *15* of the clutch *A*, to stop the delivering-rolls, as described.

6. The cup *16*, bevelled surface *15*, in combination with the clutch *A* and lever *B*, arranged and operating substantially as described.

7. The wheel P, lever V, finger S, cam P, and lever X, arranged and operating substantially as described, for the purpose of regulating the head-twist.
8. The wheel P and lever V, in combination with cam W, substantially as described.
9. The shell a, worm b, shaft c, wheel e, gear f, cam W, rack g, slide-bar i, finger l, and stand 30, arranged and operating substantially as described.
10. The shell a, in combination with the shaft c and cam W, as described.
11. The latch m, finger l, slide-bar i, bar h, and rack g, in combination, substantially as and for the purpose specified.
12. The combination of latch m and lever X, having the finger 32, substantially as and for the purpose described.
13. The spring r, in combination with the plate o, latch 21, and ratchet-gear 22, substantially as described.
14. The cone-pulley s, clutch t, or its equivalent,

forked lever u, and cam 40, operating substantially as and for the purpose set forth.

15. The chain-gear 12, chain 14, in combination with screw 11, nut 10, and shipper 7, substantially as described.

16. The pulley 41, loose on the hub of friction-clutch t, in combination with pulley s, substantially as described.

17. The pulley W², in combination with cone-pulley s, and friction-clutch t, substantially as described.

18. The cone-pulley s, in combination with the gear 80 and pulley W², substantially as described.

19. The scrolls 83 and 84, in combination with the cone-pulleys s and 20.

The above specification signed by me, this 5th day of February, 1869.

SETH D. PAUL.
